UNITED STATES PATENT OFFICE.

WILLIAM G. TUTEN, OF BONNET, SOUTH CAROLINA.

BALING-PRESS.

SPECIFICATION forming part of Letters Patent No. 457,173, dated August 4, 1891.

Application filed December 24, 1890. Serial No. 375,691. (No model.)

To all whom it may concern:

Be it known that I, WILLIAM G. TUTEN, a citizen of the United States of America, residing at Bonnet, in the county of Hampton 5 and State of South Carolina, have invented certain new and useful Improvements in Bal-
ing-Presses; and I do hereby declare the fol-
lowing to be a full, clear, and exact descrip-
tion of the invention, such as will enable others
10 skilled in the art to which it appertains to
make and use the same, reference being had to
the accompanying drawings, and to letters
of reference marked thereon, which form a part
of this specification.

15 This invention relates to improvements in
baling-presses.

The object of the invention is to provide a
press having double baling-boxes supported
20 to revolve horizontally, the boxes being con-
structed and arranged so that when one is
under the screw or press power the other will
be in a position to be filled; and it consists
25 in the construction and combination of the
parts, as will be hereinafter fully set forth
and particularly claimed.

In the accompanying drawings, forming a
part of this specification, Figure 1 is a side
30 view of a baling-press constructed in accord-
ance with my invention, one of the boxes be-
ing shown under the screw or press power.
Fig. 2 is a vertical sectional view through the
line $x x$ of Fig. 1. Fig. 3 is a detail perspec-
35 tive view of the lower portion of one of the
baling-boxes.

35 A refers to the main supporting-frame for
the baling-boxes, which preferably consists of
horizontal sill-pieces $a a$, which rest upon the
transverse beams a' , uprights $b b'$, transverse
40 strips c , and upper horizontal beams c' and
 c^2 . Between a pair of the beams a is pivoted
a rock-bar d , to which is secured one end of
a lever D , in which is stepped a pin e , which
forms one of the pivots for the revolving
45 frame carrying the baling-boxes. This pivot
passes through a transverse board d' and into
a socket formed in the center beam of the
frame carrying the baling-boxes, the said
board d' serving as a guide for the pivot-pin.
50 The outer end of the lever D when lowered
rests in a recess in one of the longitudinal
beams a . Centrally the upper portion of the
frame carrying the baling-boxes is provided

with a pivot E , which is rigidly secured to
suitable brace-pieces, and the upper end
thereof is reduced to provide a shoulder f , 55
the reduced end passing through an aperture
in the beam c^2 , the shoulder limiting the up-
ward movement of the frame.

F refers to a lever fulcrumed near one
end of the upper beam c^2 , which is connected 60
by a flexible connection D' to the lever D ,
and the lever F is adapted to be held in a
depressed position by being passed beneath
a suitable catch f' , located near the opposite
65 end of the beam c^2 , to which said lever is ful-
crumed. When the long end of the lever is
depressed, the frame carrying the baling-
boxes is elevated through the medium of the
lever D , and can be revolved upon its pivots,
70 and when said lever is released the revolving
frame will be lowered to rest upon the cross-
beams a , and thereby relieve the pivot-pins
of all strain or pressure.

The revolving frame G , which carries the
baling-boxes, is made up of a suitable number 75
of transverse beams $g g$, above which is lo-
cated a floor h and frames, as shown, for the
support of the baling-boxes. To the floor h
are secured blocks $i i$, to which the side doors
80 I of the baling-boxes are pivotally secured,
the end doors I' resting at their lower ends
against blocks i' and the vertical edges of the
doors I. The side doors I are provided near
85 their upper ends with transverse strips l ,
which project beyond said doors, and near
their outer ends are provided with notches
 m , these notches on one of the cross-strips be-
ing in the upper edge thereof, while they are
in the under edge of the opposite strip. With
these notches the locking-bars M , pivoted to 90
the end doors I' , engage to hold the doors or
four walls of the baling-box together. Above
the knockdown baling-box is rigidly secured
the stationary box K . If desirable, one of
the strips l may be provided with levers L 95
for tripping the locking-bars M .

At a suitable distance below the upper ends
of the stationary boxes K , I provide a plat-
form N , upon which the operators may stand
while filling the boxes, and this platform is 100
provided adjacent its periphery at diamet-
rically-opposite points with blocks $o o$, adapt-
ed to be engaged by a pivoted catch O , piv-
oted to one side of the frame A , and when

this catch is in engagement with one of the blocks one of the baling-boxes will be located under the screw which carries the follower or packer, this screw being suitably journaled 5 to the main frame between the upper beams c' , so that the follower can be elevated sufficiently to be entirely clear of the baling-boxes. The gear-wheel for operating the screw-threaded shaft carrying the follower is 10 mounted on the beams c' and is driven by a power-shaft through the connection of the pinion, as shown.

In practice a baling-press constructed as hereinbefore described will be of such a size 15 that a person can stand upon the platform N and fill one of the baling-boxes while the material in the opposite one is being pressed. The sides and ends of the knockdown baling-box are so constructed that they will drop 20 when the catches for holding them in a vertical position are released and the bale readily removed after being bound.

I am aware that prior to my invention it has been proposed to provide cotton-presses 25 with a frame which supports baling-boxes which can be revolved and held in position, so that a fixed follower can operate in either box, as will more fully appear by reference to the patent to T. E. Wolf, No. 425,481, dated 30 April 15, 1890, and I therefore do not claim such a baling-press broadly as my invention; but

What I do claim as new, and desire to secure by Letters Patent, is—

1. The combination, in a baling-press having 35 revolving baling-boxes, of a rigid frame within which the baling-boxes and parts carried thereby are pivotally secured, the revolv-

ing baling-boxes having a circular platform, levers D and F , fulcrumed upon the rigid frame and connected to each other, and a catch f , carried by the rigid frame, with which the long end of the lever F is adapted to engage, the revolving baling-boxes being adapted to be supported by the lever D when the long end of the lever F is depressed, substantially 45 as set forth.

2. In a baling-press, the combination of a rigid frame having centrally pivoted therein a revolving frame carrying baling-boxes, a rock-shaft pivoted to the base of the rigid 50 frame, a lever D , carrying a pivot-pin e , and a flexible connection D' , attached to the long end of the lever D and with the short end of a lever F , said lever F being pivoted to the upper portion of the rigid frame, so that the 55 long end thereof will be within reach of an operator standing on the platform, the upper pivot-pin e passing through the rigid frame and having a reduced upper end forming a shoulder for limiting the upward movement 60 of the revolving frame, together with a follower carried by the rigid frame and a circular platform carried by the baling-boxes, having projections o for engagement with the catches on the rigid frame, the parts being organized substantially as shown, and for the 65 purpose set forth.

In testimony whereof I affix my signature in presence of two witnesses.

WILLIAM G. TUTEN.
